P. GERMASZEWSKI.
WALL PAPER HANGING IMPLEMENT.
APPLICATION FILED AUG. 15, 1919.

1,346,647.

Patented July 13, 1920.

UNITED STATES PATENT OFFICE.

PIOTER GERMASZEWSKI, OF SOUTH EAST CLEVELAND, OHIO.

WALL-PAPER-HANGING IMPLEMENT.

1,346,647.

Specification of Letters Patent.

Patented July 13, 1920.

Application filed August 15, 1919. Serial No. 317,675.

To all whom it may concern:

Be it known that I, PIOTER GERMASZEWSKI, a citizen of the United States, residing at South East Cleveland, county of Cuyahoga, and State of Ohio, have invented certain new and useful Improvements in Wall-Paper-Hanging Implements, of which the following is a specification.

This invention has for its object the provision of an apparatus for hanging blanks of wall paper upon a vertical wall in an easy and rapid manner.

A further object is to provide an apparatus for applying paste in desirable quantities to the back side of the paper blanks, means being also provided for carrying the blanks and for trimming the edges at the time of application.

These and other like objects, which will become more fully apparent as the description progresses, are attained by the novel construction and combination of parts hereinafter described and shown in the accompanying drawings, forming a material part 25 of this disclosure, and in which—

Figure 1 is a side elevational view showing a paper hanging device made in accordance with the invention, and

Fig. 2 is a front elevational view of the same.

Referring to the drawings in detail, the numeral 10 indicates a wall upon which the blanks are to be affixed, and 11 the paper applied thereto.

The device for applying the paper comprises a handle 12 which may be of any convenient length so as to reach the upper portion of the wall, the handle having a rectangular upper portion 13 from which extend on both sides pairs of forked bars 14 and 15, respectively lower and upper, the outer ends of these bars being secured to side plates 16 and 17, respectively right and left.

These side plates are substantially rectangular with outer rounded corners and mounted therein, near the bars 14, is a removable slotted spindle 18, adapted to receive the roll of paper 19, the extended end of which passes against a roller 20, the spindles 21 of which are journaled in the side plates 16 and 17. The paper then passes over another roller 22, having spindles 23, and then over an end roller 24, having spindles 25, a similar roller 26 being

mounted on spindles 27, the spindles 25 and 27 extending beyond the side plate 17.

A paste supplying tank 28 having a bottom, sides and ends is secured between the plates 16 and 17 and mounted so as to rotate therein is a brush 29 together with a flexible wiper 30, controlled by a transverse rod 31, held in adjustment by the extending thumb screws 32, so that more or less of the paste may be applied to the surface of the paper, the wiper making contact with the bristles of the brush 29, so as to remove any excess and distribute the paste evenly.

Upon one extending end of the spindle 25 is secured a sprocket 33 over which is trained a chain 34, the chain engaging with another sprocket 35, fixed upon the spindle 21 and then passing over another sprocket 36, fixed upon one extending end of the brush 29, so as to cause the brush to rotate when the rollers 24 are in frictional contact with the walls to which they may be pressed when in use.

In order to obtain proper tension upon the paper, disposed from the roll 19, a spindle 37 is journaled in the side frames, the same carrying an extending plate 38, disposed between the side plates, and at the center of the spindle 37 is fixed a drum 39, engaged with cords 40, trained over carrier pulley 41, mounted in the extreme end of the handle element 13, the cords 40 being engageable with a fixed button 42 secured upon the lower end of the operating handle 12, the arrangement being such that as either of the cords 40 is pulled, the edge of the plate 38 may be moved relatively to the paper passing therebelow so as to tension the same to any desired extent.

In operation, the paste reservoir or tank 28 having been partially filled with a quantity of the paste and the wall paper roll disposed upon the spindle 18, the ends being passed over the several rollers, it will be clear that when the rollers 24 and 26 are rotated the same will convey motion to the several rollers secured between the side plates, moving the paper along, covered with an adhesive, and also that the paper may be tensioned as desired, the movement being merely to raise and lower the handle 12.

In addition, a pair of knives 43 are placed closely adjacent to the inner walls of the frame, the same being carried on spindles 44, which extend through said frame and are 110

provided with wing nuts 45 by which they may be adjusted, and when adjustment is made they are held in position by reason of ratchets 46, which are engaged with spring actuated pawls 47 so as to hold the same in position for properly cutting the margins of the paper, it being understood that the blank is hung from the bottom and the apparatus moved upwardly, simultaneously securing the blank to the wall and severing the edges in an obvious manner by the sharpened backs of the knives.

Having thus described my invention what I claim as new and desire to secure by Letters Patent, is—

In a wall-paper hanging implement, the combination with a handle adapted for manual operation, a pair of side plates car-

ried in spaced relation by said handle adapted to receive a roll of paper therebetween, 20 and means for supporting a roll of paper, of a paste supplying tank, a brush rotatable therein, means for rotating said brush, a wiper adapted to remove surplus paste from said brush, rollers for pressing the paper 25 upon the wall, a plate having an edge adapted to make contact with the paper, means for manipulating said plate whereby more or less pressure may be attained, and a pair of cutters adapted to sever the marginal 30 edges of the paper when said implement is moved upward.

In testimony whereof I have affixed my signature.

PIOTER GERMASZEWSKI.
